UNITED STATES PATENT OFFICE

157,181

DISPLAY FIGURE UNIT OR THE LIKE

Florence S. Moulson, Rehoboth, Mass., assignor to
B. A. Ballou & Co. Incorporated, a corporation of Rhode Island

Application March 31, 1949, Serial No. 1,728

Term of patent 3½ years

(Cl. D1—2)

To all whom it may concern:

Be it known that I, Florence S. Moulson, a citizen of the United States of America, residing at Rehoboth, county of Bristol, State of Massachusetts, have invented a new, original, and ornamental Design for a Display Figure Unit or the like, of which the following is a specification, reference being had to the accompanying drawing, forming a part thereof.

Fig. 1 is a front view of a display figure unit or the like, showing my new design;

Fig. 2 is a side view on line 2—2 of Fig. 1; and

Fig. 3 is a side view looking on line 3—3 of Fig. 1.

I claim:

The ornamental design for a display figure unit or the like, substantially as shown.

FLORENCE S. MOULSON.
